APPARATUS FOR AUTOMATICALLY EXPOSING SENSITIZED PLATES FOR X-RAY PHOTOGRAPHY

George Yates, Glendale, Calif.

Application May 24, 1949, Serial No. 2,847

Term of patent 14 years

(Cl. D61—1)

To all whom it may concern:

Be it known that I, George Yates, a citizen of the United States, and a resident of Glendale, California, have invented a new, original, and ornamental Design for an Apparatus for Automatically Exposing Sensitized Plates for X-Ray Photography, of which the following is a specification, reference being had to the accompanying drawing, forming part thereof.

Referring to the drawing:

Figure 1 is a perspective view of an apparatus for automatically exposing sensitized plates for X-ray photography showing my new design;

Figure 2 is an elevation of one end of the device as seen from the right of Figure 3;

Figure 3 is a side elevation of the device as viewed from the right of Figure 1; and

Figure 4 is a top plan view thereof.

I claim:

The ornamental design for an apparatus for automatically exposing sensitized plates for X-ray photography, as shown.

GEORGE YATES.
